CLAIM

The ornamental design for a fireplace logset burner unit, as shown and described.

DESCRIPTION

FIG. 1 is a front perspective view of the fireplace logset burner unit of the present invention;

FIG. 2 is a top plan view of the fireplace logset burner unit of FIG. 1;

FIG. 3 is a left side view of the fireplace logset burner unit of FIG. 1, the right side view being a mirror image thereof; and,

FIG. 4 is a bottom view of the fireplace logset burner unit of FIG. 1.

The broken line showing of logs is for illustrative purposes only and forms no part of the claimed design.
